UNITED STATES PATENT OFFICE.

LÉON DION, OF WILKES-BARRE, PENNSYLVANIA, ASSIGNOR TO THE AMERICUS ELECTRO-HERMETIC COMPANY, OF WILKES-BARRE, PENNSYLVANIA.

MECHANISM FOR RECOVERING, TRANSFORMING, AND CONSERVING ENERGY.

No. 895,006.

Specification of Letters Patent.

Patented Aug. 4, 1908.

Application filed May 8, 1908. Serial No. 315,748.

To all whom it may concern:

Be it known that I, LÉON DION, a citizen of the United States, and a resident of Wilkes-Barre, in the county of Luzerne and State of Pennsylvania, have invented certain new and useful Improvements in Mechanism for Recovering, Transforming, and Conserving Energy, of which the following is a specification.

10 In the water service of dwellings and other buildings the water is, as is well known, usually supplied to the pipes under considerable pressure, to the end that it may reach the upper stories, and, in that condition, is possessed of more or less potentiality as a force, depending of course upon the pressure in which it is supplied to the pipes and is maintained in them. The force thus contained in the water, whether under greater or less pressure, has been found to be considerable, and efforts have heretofore been put forth to utilize this force; by arranging at some particular point in the pipes a water motor, which coöperated with an electric generator, to conserve such force in the form of an electric current, which was stored up in an accumulator and subsequently used for illuminating and other purposes. This arrangement, while efficient to a certain degree, 25 was operative at only one particular point in the piping of a house or other structure, and so recovered and conserved the energy exerted by the water in passing through the pipe at that particular point alone.

30 The object of my invention is therefore to increase this efficiency, by locating a water motor and generator not only in the pipe which enters the house or other structure, or in the common stand pipe leading therefrom, but also in the individual pipes leading from this inlet pipe, or from the stand pipe, to the various lavatory devices or to the other water receiving receptacles made use of in a dwelling or other structure.

35 To these ends, the invention consists in the peculiar arrangement of the inlet and distributing or connecting pipes, motors, electric generators, valves, circuit makers and breakers, and an electro-magnet, with respect to the various lavatory devices or other water receiving receptacles of a dwelling or other appropriate building, and to a storage battery or accumulator, whereby when the circuit in which any one of 50 the valves and lavatory devices or water

receptacles is located is made or broken by the operation of such valves, the circuit in which the generator in the inlet or supply pipe is located is automatically made or broken in correspondence therewith, through the electro-magnet, all as will hereinafter more fully appear.

Referring to the accompanying drawings, in which my invention is illustrated, Figure 1, is a sectional elevation of two floors of a dwelling house or other building, showing my invention applied in connection with a water cooler, a sink, a bath tub, a wash stand and a water closet, which several devices are shown in elevation with certain of the parts broken away for purpose of illustration. Fig. 2, a vertical section of one form of water motor, which may be employed in connection with my invention, the induction and eduction pipes being shown in elevation, and Fig. 3, is a front elevation of one of the valves or faucets, which may be employed in connection with the water purifier, the sink, the bath tub, and wash stand, showing also portions of the electric conductors by means of which any one of the electric generators may be brought into circuit with the storage battery or accumulator when its valve is opened and such circuit broken when the valve is closed.

In all the figures like letters of reference are employed to designate corresponding parts.

A and A' indicate the floors of a dwelling house or other appropriate building, and B, C, D, E, and F, indicate respectively a water-cooler or purifier, a sink, a bath tub, a wash-stand, and a water closet, which several devices when collectively referred to herein will, for convenience of description, be designated as "receptacles", and which are or may be of any ordinary or preferred construction. In the drawing I have shown these receptacles as disposed on different floors, with those on the same floor more or less juxtaposed, but this arrangement, as is obvious, is for convenience of illustration and other dispositions of them may be adopted, as the arrangement of rooms in the dwelling or other building in which they are employed, or the convenience of their operation may suggest. For connecting these several receptacles with the source of water supply, various arrangements of piping may be selected. In the drawings, however, I have shown this connection effected through the

intervention of a common stand pipe H, which is provided with laterally extended branches I and I¹, and is connected with the water main or other source of supply through an inlet pipe K. As thus arranged, each of the receptacles is connected with one or the other of these branches I and I¹ by short connecting pipes a, extending upward from its appropriate branch, with its upper end overturned whereby to discharge the water into the interior of its respective receptacle, and is provided with an appropriate valve or faucet b through which the flow of water through its respective pipe may be regulated and controlled. With the connection of the various receptacles with the source of water supply thus effected, the flow of the water to their interiors will be accomplished by opening their appropriate valves when the flow of water along the stand pipe and through its branches and connection to the interior of the receptacles will be permitted, and in order to avail of the movement of the water along the pipes to generate power, I interpose in such pipes at suitable points water motors L. These water motors may be of any ordinary or approved forms, and in the drawings I have shown a well known form thereof, which consists of a circular disk c, journaled eccentrically within a circular casing c¹, upon a shaft c², and as provided with radial floats c³ extended therefrom and fitted to slide inwardly and outwardly in suitable grooves c⁴ formed therein, with these floats held normally pressed outward and their outer ends in contact with the interior of the casing c¹, by spiral springs c⁵ interposed between their inner ends and the bottom of the grooves c⁴ in which they are respectively disposed. As thus arranged and provided, the periphery of the disk c runs in contact with the interior surfaces of the casing c¹ at the point nearest approach of the casing to the shaft c², as shown at c⁶ in Fig. 2, whereby to prevent the passage of the water between the disk and casing at that point, while at all other points the periphery of the disk is more or less remote from the interior of the casing, forming thereby a passage-way c⁷ through which the water admitted at the point of ingress *, through either the inlet pipe K or one of the branch pipes I or I¹, flows to the point ** of egress, which is or may be connected with either the stand pipe H or one of the short connecting pipes a, as may be desired. Across the passage-way c⁷, as thus formed however, extend the floats c³, against which the water impinges as it flows through such passage-way from the point of ingress to the point of egress, carrying forward with it in its movement the successive floats c³, and thereby rotating the disk c with its carrying shaft c². With the rotation of the disk thus effected, and the outer ends of the floats held at all times in contact with the interior of the

casing, these floats during the rotation of the disk are alternately forced inward and outward by the alternate action of the casing and of their respective springs, as the floats are carried successively around to the point 70 of contact c⁸ of the periphery of the disk with the interior of the casing, and passed beyond it, with the result that in all positions they may occupy in revolving with the disk the water is prevented from passing them in its 75 travels through the passage-ways c⁷. In thus flowing through the passage-way c⁷, and effecting the rotation of the disk c, the travel of the water around the disk is continued until it arrives at the point c⁹, where the periphery of the disk runs in contact with the interior of the casing, when it is arrested, as by an abutment, and its further flow caused to take place through the point of egress ** and thence through the pipe leading therefrom. While thus the contact of the periphery of the disk c with the interior of the casing c¹ at the point c⁹, acts as an abutment to prevent the flow of the water around the disk in a forward direction beyond that point, it 90 also serves as an abutment against which the water entering the casing through the point of ingress * acts to prevent it from flowing around in a backward direction through that point, and causes it to exert its pressure 95 around in the opposite direction against the floats, to cause the rotation of the disk as it flows through the casing along the passage-way c⁷.

With the motors of the above or other construction, they are preferably located at the junction of the inlet pipe K with the stand pipe H, and at the junctions of the short connecting pipes a of the respective water cooler or purifier B, the sink C, the bath-tub D, the wash-stand E, and the water-closet F, with their respective co-operating branch pipes I and I¹, as shown at L, L¹, L², L³, L⁴ and L⁵. As thus arranged, whenever the valve in any one of the short pipes a is opened, and the flow of water through the latter and through the inlet pipe is permitted, the operation of the respective motors in that particular short pipe and in the inlet pipe will be effected, and the same continued until the valve is closed 110 and the flow of water through those pipes thereby interrupted, when the operation of the motors will cease, to be again resumed when the valve is again opened, and so on.

For transforming the power exerted by the 120 motors into electricity, when the motors or any of them are in operation, I employ electric generators, which are preferably in the shape of dynamos, and store up the current thus generated in an appropriate storage battery or batteries.

With the motors located as above explained, the electric generators d, e, f, g, h, and i may be disposed either upon the shafts c² of their respective motors, or be sep- 130

arated therefrom and operated through intermediate mechanism. In the drawing I have shown the electric generator *d* as separated from its operating motor *L*, and operated from it through the intervention of an endless belt *l*, while the generators *L¹*, *L²*, *L³*, *L⁴*, and *L⁵* I have illustrated as mounted upon shafts *c²* of their respective motors, and either or both of these arrangements may be adopted 13 in practice as may be preferred.

With the electric generators operated as above described, I employ a storage battery or accumulator *M*, in which the electric current generated by the generator or generators 15 is stored. This storage battery will, in practice, be made up of the proper number of elements to suit it to the position in which it is to be employed, with such elements inclosed within a single cell or a plurality of cells, as 20 may be preferred. As thus employed, this storage battery is connected with each of the generators *d*, *e*, *f*, *g*, *h*, and *i* by appropriate conductors *r* and *s*, of which the conductor *r* extends from the positive or + pole of the 25 storage battery *M* to the corresponding positive poles of the different generators, while the conductors *s* extend from the negative or - pole of such battery to their corresponding negative poles. With the storage battery 30 *M* thus connected with the different generators, whenever the water is flowing through the stand pipe *H*, and through either of the branches *I* or *I¹* and any of the short connecting pipes *a*, the motors appropriate to 35 that particular pipe *a*, and to the inlet and stand pipes, will be operated with their attached generators, and the electric current generated thereby will pass through its appropriate conductors *r* and *s* to the storage battery *M*, where it will be stored for subsequent 40 use. The current thus generated will continue to travel along its appropriate conductors to the storage battery, so long as the water is allowed to flow through the pipes appropriate 45 to those motors, but will cease to travel immediately the flow of water through them is arrested. Immediate however the motion of the motors and generators is arrested, the charge of electricity stored up in the storage 50 battery would begin to discharge itself through the circuit formed by the conductors *r* and *s* and the different generators, if no provision was made for breaking these circuits when the motors and their respective 55 generators are arrested in their movements. In order therefore to provide for making and breaking the circuit in which each of the generators is arranged, I equip each of these circuits with a circuit maker and 60 breaker, which is so constructed and arranged that, when the generator is brought into operation, the circuit in which it is arranged will be closed and broken when its operation ceases. The form of this circuit breaker may be modified in various

ways to suit it to the location in which it is to be employed, and in the circuits in which the generators *e*, *f*, *g*, and *h*, appropriate to the water cooler or purifier *B*, the sink *C*, the bath tub *D*, the wash stand *E*, are employed, 70 it is formed upon and applied to the valves or faucets *b* of their respective short connecting pipes *a*, with the globes or bodies *b¹* of the valves or faucets connected with the proper poles of their respective generators by conductors *r¹*, and their stems or movable members *b²* provided with projecting lugs *b⁴*, for contact with the free ends of the short conductors *r²* leading to the conductor *r*, as shown. As thus constructed and arranged, 80 when any one of these valves or faucet *b* is closed, and the flow of the water through the same is arrested, the projecting lug *b⁴* is removed from contact with the free end of the conductor *r²*, as shown in Fig. 3, and the circuit through that valve or faucet is broken. On the other hand, when the valve or faucet is open to allow of the water flowing through its appropriate pipe *a*, the projecting lug *b⁴* will be brought around in contact with the 90 free end of the conductor *r²*, and the circuit in which that valve or faucet is arranged will be closed. In this condition the circuit will remain until the valve is again closed, when the projecting lug *b⁴* will again be removed 95 from contact with the free end of the conductor *r²* and the circuit through that valve or faucet will be again broken. Thus, as will be seen, the making and the breaking of the circuits through the valves or faucets *b* will 100 be effected when the valves or faucets are respectively opened and closed to permit of the flow of the water through their respective pipes *a*, and the arrest of such flow.

The making and breaking of the circuits in 105 which the valves or faucets *b* are located being thus effected as above pointed out, the making and breaking of the circuit in which the generator *i* is located is accomplished through the instrumentality of the flushing 110 lever *t*, to which is connected one end of the short conductor *r³*, leading from the proper pole of the generator *i*, with such lever co-operating with the free end of the conductor *r⁴* connected with the conductor *r*. In its 115 normal position and when the generator *i* is at rest, the flushing lever *t* will be removed from its contact with the free end of the short conductor *r⁴*, and the circuit in which this generator *i* is arranged is broken. On the 120 other hand, when the outer end of this flushing lever is depressed, to flush the water closet and thereby starts the generator *i*, the lever *t* is brought in contact with the free end of the conductor *r⁴*, and the circuit in which the generator *i* is arranged thereby brought 125 into circuit with the storage battery *M*. With this construction, as will be seen, the making and breaking of the circuit in which the generator *i* is arranged is alternately ac- 130

complished by bringing the flushing lever *t* into contact with the free end of the conductor *r*, and carrying it out of contact therewith, by respectively depressing and 5 raising its outer free end.

While, the electric generators *e, f, g, h*, and *i* are thus brought into and carried out of circuit with the storage battery *M*, the circuit in which the generator *d* is arranged is 10 made and broken through the intervention of a spring plate *u*, which co-operates with the free ends of the short conductors *r⁵* and *r⁶*, that respectively extend from the proper poles of the generator, and from the co-operating poles of the battery, as shown.

In its normal position, as when the generator *d* is at rest, the spring-plate *u* is by its own resiliency removed from contact with the ends of the conductors *r⁵* and *r⁶*, as shown 15 by dotted lines in Fig. 1, and the circuit in which the generator *d* is arranged is thereby broken. On the other hand, whenever the generator *d* is brought into operation by the flow of water through the pipes *K* and *H*, the 20 spring-plate *u* will be carried in contact with the terminals at the end of these conductors by an electro-magnet, of the ordinary or solenoid form, as shown at *N*, and located in the conductors *r*, through which solenoid 25 works a core or armature *v*, as is common to devices of that class as heretofore employed.

With the parts arranged and constructed as above explained I am able, as will be seen to recover the energy stored up in the water 30 in the service pipes of residences and other buildings, at two points, whenever any one of the valves in the short connecting pipes *a* are opened to allow of the flow of water through it, and, after having transformed it, 35 to conserve the energy for subsequent use. The energy thus recovered and conserved in the form of electricity is applicable to any of the uses and purposes to which the electric current is usually applied, and in Fig. 1 of the 40 drawings, I have shown it as employed for the purposes of illumination, *O* and *P* being conductors or leads, which are respectively connected at one of their ends to the positive and negative poles of the storage battery *M*, 45 with electric lamps *w* interposed between them in multiple arcs as is common with electric lighting systems as ordinarily in use. As thus arranged whenever the electric current is stored in the storage battery or 50 accumulator *M* it will pass outward along the appropriate lead or conductor and cause the lamps to glow; and in order to permit of the lamps being brought into and carried out of operation when required, I provide one of 55

the conductors or leads, as, for instance, the conductor or lead *O*, with an appropriate switch *x*, through which the circuit in which that conductor or lead is included may be opened and closed as may be desired by manipulating the switch in the required direction.

While in the drawings I have shown, and in the foregoing described my invention as applied in connection with a water-cooler or purifier, a sink, a bath tub, a wash bowl, and a water closet, and the electric current generated and stored up in the storage battery employed for electric lighting, it is to be understood that this is merely illustrative, and that the invention may be employed in connection with any other water receiving receptacles, with which the service pipe may be connected, and the current generated and conserved applied to other purposes than that specifically stated.

Having now described my invention and specified certain of the ways in which it is or may be carried into effect, I claim and desire to secure by Letters Patent of the United States,

The combination, with the lavatory devices and other water receiving receptacles of a dwelling or other similar structure, the inlet pipe of a water service, and connecting pipes intermediate such inlet pipe and the various lavatory devices and other water receiving receptacles, of a water motor and electric generator located in each of these connecting pipes and in the inlet pipe, a valve provided with a circuit maker and breaker located in each of such connecting pipes, an accumulator or storage battery, electric connections intermediate the several valves and the accumulator or storage battery, a circuit maker and breaker arranged in connection with the electric generator of the inlet pipe, and an electro-magnet arranged in circuit with the several valves for operating the last mentioned circuit maker and breaker, whereby, when the circuit in which any one of the valves is located is made or broken by the operation of its respective valve, the circuit in which the generator in the inlet pipe is located is automatically made or broken in correspondence therewith through the electro-magnet, substantially as described.

In witness whereof I have hereunto set my hand this 4th day of May, 1906.

LEON DION.
